JOLT MOLDING MACHINE

Lester C. Young, Cleveland, Ohio, assignor to
Spo, Inc., a corporation of Ohio

Application February 20, 1946, Serial No. 648,997

5 Claims. (Cl. 22—45)

1 My invention relates to molding machines and more particularly to jolt molding machines adapted to aid in compacting the molding sand or other material.

This application replaces my abandoned application; Serial No. 481,239 filed March 31, 1943.

In jolt molding machines, the jolt table is raised by a fluid pressure lifting means which comprises a piston element and a cylinder element adapted to be extended relative to each other and defining an extensible fluid pressure chamber. For the raising movement of the jolt table, fluid under pressure is introduced into the extensible fluid pressure chamber to raise the jolt table relative to an anvil upon which the jolt table rests in its lowermost position. In operation, the jolt table is raised a predetermined distance above the anvil, and then the fluid is exhausted from the fluid lifting chamber, which permits the jolt table to fall by gravity and strike the anvil for producing a jolting operation to aid in compacting the molding sand or other material in the molding flask or other container. As the piston and cylinder move extensively relative to each other for raising the jolt table, there is an exposure of the relative movable portion of the piston. This exposed portion of the piston is normally subjected to a considerable amount of molding sand or other foreign abrasive materials which comes in contact therewith during the jolting operations of the molding sand and which if not prevented causes a great deal of excessive wear.

An object of my invention is to provide a construction which shields the exposed portion of the relatively movable piston of the lifting means during the jolting operations.

Another object of my invention is the provision of an anvil which is separated from the lifting means that raises the jolt table.

Another object of my invention is the provision of a shield which surrounds the lifting means for the jolt table to protect the relatively movable exposed portion of the lifting means from sand or other foreign material during operation, the shield functioning also as an anvil upon which the jolt table may strike to aid in compacting the molding sand or other material.

Another object of my invention is to exhaust the compressed air or other fluid from the lifting means in such a direction and locality as to prevent any molding sand or other foreign material from contacting the relatively movable parts of the lifting means.

Another object of my invention is the provision of an oil or lubricant reservoir into which the

2 relatively movable parts of the lifting means may be immersed in order to provide complete lubrication for the relatively movable parts of the lifting means.

Another object of my invention is the provision of exhausting the compressed air or other fluid outwardly through the region where the jolt table strikes the anvil, which comprises the upper end of the shell or shield which surrounds the lifting means, so that just prior to the time the jolt table strikes the anvil, exhaust air is flowing outwardly to prevent any molding sand or foreign material from entering the surrounding chamber during the descending movements of the jolt table.

Another object of my invention is to avoid the construction of employing the relatively movable parts of the lifting means as the anvil and hammer for producing the jolt on the work table, thereby eliminating the peening of the members which might otherwise interfere with the reciprocal movements of the relatively movable parts of the lifting means.

Another object of my invention is the provision of a jolt table having at least two annular reinforcing ribs which project downwardly from the underneath side of the jolting table, the inner rib terminating in the cylinder which comprises part of the lifting means, and the outer rib terminating in a hammer surface for striking an anvil.

Another object of the present invention is to provide an improved means for lubricating the relatively movable parts of the jolt machine by admitting to the air supply, a predetermined quantity of oil and introducing the oil laden air into the piston chamber where it will flow downwardly between the piston and cylinder by the air pressure.

Another object of the present invention is to provide an oil chamber within the shield, so that the oil contained therein may contact the exposed part of the piston during the jolting operation.

Another object of the present invention is to provide a jolt machine of the type referred to having a stationary piston which is removably mounted on the machine in a manner to afford replacement and installation in a simple and efficient manner.

Other objects and a fuller understanding may be had by referring to the following description and claims taken in conjunction with the accompanying drawings in which:

Figure 1 is a front elevational view of a jolt molding machine, the right half being shown in cross-section to illustrate the construction of

the parts, the section being taken along the line 2—2 of Figure 2;

Figure 2 is a top plan view of a jolt molding machine embodying the features of my invention;

Figure 3 is a side elevational view of the machine shown in Figure 1; and

Figure 4 is a transverse cross-sectional view, taken along the line 4—4 of Figure 2, and showing further details of the structure.

With reference to the drawings, my jolt machine comprises generally a base 10, a jolt table 24, a fluid pressure lifting mechanism comprising a piston 18 and a cylinder 29 interposed between the base 10 and the jolt table 24, an outer 15 tubular shell 11 projecting upwardly from the base and terminating in an anvil 12 against which the jolt table strikes to aid in compacting the molding sand or other material.

The base 10 may be of any suitable shape and has a relatively flat bottom adapted to rest upon a suitable foundation, and is preferably constructed of a semi-steel casting. The outer tubular shell 11 may be integrally formed with the base 10 and projects upwardly therefrom and serves not only as an anvil against which the jolt 20 table 24 may strike, but also as a protecting table to prevent molding sand or other foreign shield to prevent abrasive substances from coming in contact with the relatively movable parts of the piston 18 and cylinder 29 which comprise the fluid pressure lifting mechanism for the jolt table. The upper end of the anvil 12 is provided with a flat annular face 13 against which the jolt table strikes. The base 10 is further formed with an inner tubular extension 14 which projects axially upwardly therefrom for a relatively short 25 distance, there being a plurality of webs 15 between the adjacent inner and outer tubular members and spaced apart in angular relation. The base 10 is further formed with a bore 16 extending upwardly from its flat bottom, and the bottom of the bore adjacent the inner extension 14 is provided with a flat annular attaching face 17.

A piston 18 has its lower portion securely mounted in the inner tubular extension 14 and its lower portion is closed by an integral end wall 19. The lower end of the piston 18 is further provided with an integral outwardly extending marginal flange 20 having a flat annular face which engages the adjacent attaching face 17 and which is secured to the base 10 by a plurality of machine screws 21 or any other suitable means. The piston is thus readily removable. The upper end of the piston 18 is open and projects beyond the annular face 13 of the anvil 12. As shown in Figures 1 and 4, the piston 18 is provided with an integral transversely extending partition 22 spaced intermediate the two ends of the piston. A tapped opening is provided in the partition 22 and is normally closed by a threaded plug 23.

The jolt table 24 is preferably constructed of a semi-steel casting and is disposed to rest upon the anvil 12 of the upper end of the tubular shell 11 in substantially a horizontal position. The jolt table 24 has preferably a flat upper surface 25 and has upon its underneath side three annular depending flanges or ribs to reinforce the construction; namely, an outer flange 26, an intermediate flange 27 and a central flange which constitutes the cylinder 29. The outer flange 26 extends downwardly from the marginal edge of the jolt table. The flange 27 projects downwardly at an intermediate radial annular loca-

tion and constitutes a hammer for striking the anvil. The flanges are preferably integrally formed with the jolt table and aid in reinforcing the jolt table whereby it may withstand the heavy shocks to which it is subjected during the jolting operation. The annular flange or extension 27, is substantially in alignment with the anvil 12 and is provided with a flat annular face 28 adapted to strike the anvil 12 to effect 10 compacting of the molding sand or other material. The jolt cylinder 29 is preferably integrally connected to the underneath side of the jolt table 24 and constitutes a reinforcing annular rib or extension for the jolt table. The lowermost end of the jolt cylinder 29 is inwardly tapered at 30 to offer a guide when mounting the jolt cylinder 29 over the piston 18. It is to be noted that the three flanges separate from their function of reinforcing the strength of the jolt table have additional functions in that the outer flange 26 operates as an apron to guard the operator from the anvil, the inner flange 27 has the function of a hammer for striking the anvil 12, and the inner flange has the function of the cylinder 29. The cylinder is not used as a hammer and thus my construction avoids peening of the cylinder which would otherwise occur if the cylinder were used as a hammer.

The piston 18 is provided with a plurality of peripheral grooves 31, preferably adjacent to the upper end thereof, which when the machine is in operation, receive a lubricant. When the grooves are filled with the lubricant, a fluid seal is effected between the piston and the cylinder. 35 I prefer to dispense with the use of the customary piston rings because I find that when the peripheral grooves are once filled with a lubricant they function very satisfactorily for making a good seal.

Fluid under pressure is introduced into the extensible piston chamber, formed by the piston 18 and the cylinder 29, through means of an extension pipe 33 having its inner end threadably connected in an opening 32 of the wall of the piston and having its outer end passing through an opening 35 in the anvil 12. The cylinder 29 has a slot 34 provided therein through which the pipe 33 extends, so that the cylinder may not interfere with the pipe while the cylinder is being reciprocated. In operation, the jolt table is raised a predetermined amount, then the fluid within the extensible piston chamber is exhausted out through exhaust ports 37 provided in the wall of the jolt cylinder 29 at a predetermined distance below the upper end of the piston 18, when the jolt table is resting upon the anvil 12. The fluid under pressure exhausts out through these exhaust ports after the jolt table has been raised a predetermined amount and thus the jolt table is permitted to drop by gravity and strike the anvil for effecting the jolting operations to aid in compacting the molding sand or other material. The air as it exhausts from the ports 37, passes outwardly between the underneath side of the flange 27 and the top surface of the anvil 12, whereby the outward exhausting of the compressed air tends to prevent any molding sand or any other foreign abrasive materials from entering into the protecting chamber 41 which surrounds the cylinder 29 and the exposed portion of the piston 18 when the jolt table is raised.

It is noted, that the protecting chamber 41 which comprises the annular space between the 75 tubular shell 11 and the jolt cylinder 29 is sealed

or closed by the annular flange 27 resting upon the anvil 12 at the instant that the jolt occurs which is also the instance when the molding sand or other foreign materials is most apt to be flying about. That is to say, the combination of the outer annular rib 27 and the tubular shell 11 constitutes a shield for preventing molding sand or other abrasive material from coming in contact with the exposed part of the piston 18 when the cylinder 29 is raised.

In order that the wearing surface between the piston 18 and the cylinder 29 may be properly lubricated, I provide for passing the fluid under pressure, first through a fluid reservoir 38 containing a lubricant, after which the lubricant-laden air passes through a control valve 42 and a regulating valve 48 into the pipe 33. The regulating valve 48 functions to maintain the pressure of the fluid at substantially a constant value. In operating the machine, it is only necessary for the operator to open the valve 42 which admits air under pressure into the extensible fluid piston chamber for raising the jolt table 24, after which the fluid is exhausted out through the ports 37 which permit the jolt table to fall by the force of gravity and strike the anvil 12. The reciprocal operations are thus automatic. The compressed air, as it flows through the fluid reservoir 38, becomes saturated with oil so as to provide complete lubrication for the wearing surfaces between the piston 18 and the cylinder 29. The oil or other lubricant, which is carried by the fluid under pressure condenses in the upper part of the extensible piston chamber and then works its way down between the wearing surfaces of the piston 18 and the cylinder 29. The oil grooves 34 become filled with the oil which makes a good seal between the piston and the cylinder. In continuous operation, the condensed oil works its way down through the clearance between the piston and the cylinder and eventually flows down into the bottom of the protecting chamber 41 where an ample supply of oil is maintained. Preferably, the oil in the protecting chamber 41 rises to a level which is above the lowermost end of the cylinder 29 so that the exposed part of the piston is well lubricated when the cylinder 29 is raised during the jolting operation.

To assure straight movement of the jolt table 24 during the jolting operation, I employ a guide pin 51 having its upper end securely connected to the jolt table 24 and having its remaining portion adapted to reciprocate within a bushing 53 provided in a lateral extension 52 formed integrally with the anvil 12. The guide pin 51 thus operates to insure straight up-and-down movements of the jolting table during operation.

The piston 18 in my construction is readily removable and thus may be replaced by a new piston after a long period of use in actual practice. The piston may be constructed of any suitable wearing material and need not necessarily be the same material as that from which the cylinder 29 is constructed. It is to be noted that the piston and cylinder in my invention comprise essentially a lifting means which also functions as a guide means for the jolt table and is not subjected to any impact as found in prior art devices.

In the practice heretofore, considerable difficulty has been encountered in the trade with respect to the piston and cylinder wearing to such an extent that parts were required to be replaced quite frequently. With my invention, I find that the piston and cylinder wear much longer than any prior type of machine because of two main

features which are present in my invention and not present in previous types of machines; namely, (1) the protecting chamber 41 which is filled with lubricant above the section of the piston which becomes exposed when the jolt table is elevated to its uppermost position, and (2) the protecting shield 11 which prevents molding sand and other abrasive material from contacting the piston when the jolt table is raised to its uppermost position. The exposed part of the piston is always immersed in a body of lubricant which means that my construction wears very little as compared to prior art constructions. An overflow opening 39 may be provided in the shield wall 11 for lubricant to run out. Lubricant is maintained in the chamber 41 by lubricant flowing downwardly between the piston and cylinder. It is often common in prior art constructions to frequently remove the piston and replace it by an oversize piston and regrind the inside wall of the cylinder to fit the oversized piston. I find from actual experience that my construction eliminates a vast portion of this expensive repair incident to mounting oversized pistons and regrinding the inside wall of the cylinder.

Although I have described my invention in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A molding machine comprising a base, a shell projecting upwardly from said base and having at its upper end a striking anvil, a jolt table having on the underneath side thereof a surface for striking the anvil, a piston supported and carried by the base and extending upwardly therefrom toward the jolt table, a cylinder surrounding the piston for raising the table relative to the anvil, said piston and cylinder defining an extensible fluid pressure chamber, an inlet for introducing fluid under pressure into said chamber to raise the jolt table relative to the anvil, an outlet through which fluid may be exhausted from said chamber for permitting the table to return by gravity and strike the anvil, said outlet being controllable by the relative movements of the piston and the cylinder, said piston and cylinder each having a portion slidably engaging one another, said piston portion being externally exposed when said cylinder is raised, said cylinder extending downwardly from the table and terminating at a place below the anvil within said shell, whereby when the cylinder is raised the exposed portion of the piston is below the anvil and shielded by said shell.

2. A molding machine comprising a base, a shell projecting upwardly from said base and having at its upper end a striking anvil, a jolt table having on the underneath side thereof a surface for striking the anvil, a piston supported and carried by the base and extending upwardly therefrom toward the jolt table, a cylinder surrounding the piston for raising the table relative to the anvil, said piston and cylinder defining an extensible fluid pressure chamber, an inlet for introducing fluid under pressure into said chamber to raise the jolt table relative to the anvil, an outlet through which fluid may be exhausted from said chamber for permitting the table to return by gravity and strike the anvil, said outlet being

controllable by the relative movements of the piston and the cylinder, said piston and cylinder each having a portion slidably engaging one another, said piston portion being externally exposed when said cylinder is raised, said cylinder extending downwardly from the table and terminating at a place below the anvil within said shell, whereby when the cylinder is raised the exposed portion of the piston is below the anvil and shielded by said shell, said shell providing in combination with said piston a lubricant reservoir, whereby a lubricant contained therein may contact the said exposed portion of said piston.

3. A molding machine comprising a base, a shell projecting upwardly from said base and having at its upper end a striking anvil, a jolt table having on the underneath side thereof a surface for striking the anvil, a piston supported and carried by the base and extending upwardly therefrom toward the jolt table, a cylinder surrounding the piston for raising the table relative to the anvil, said piston and cylinder defining an extensible fluid pressure chamber, an air inlet for introducing fluid under pressure into said chamber to raise the jolt table relative to the anvil, the wall of said cylinder having an air outlet opening disposed a predetermined distance downwardly from the upper end of said piston which outlet is initially closed by the latter but opened upon predetermined rising of said cylinder to exhaust air from the said chamber and permit the table carried by the cylinder to return by gravity and strike the anvil, said piston and cylinder each having a portion slidably engaging one another, said piston portion being externally exposed when said cylinder is raised, said cylinder extending downwardly from the table and terminating at a place below the anvil within said shell, whereby when the cylinder is raised the exposed portion of the piston is below the anvil and shielded by said shell.

4. A molding machine comprising a base, a shell projecting upwardly from said base and having at its upper end a striking anvil, a jolt table having on the underneath side thereof a surface for striking the anvil, a piston supported and carried by the base and extending upwardly therefrom toward the jolt table, a cylinder surrounding the piston for raising the table relative to the anvil, said piston and cylinder defining an extensible fluid pressure chamber, an air inlet for introducing fluid under pressure into said chamber to raise the jolt table relative to the anvil, the wall of said cylinder having an air outlet opening disposed a predetermined distance downwardly from the upper end of said piston which outlet is initially closed by the latter

5 but opened upon predetermined rising of said cylinder to exhaust air from the said chamber and permit the table carried by the cylinder to return by gravity and strike the anvil, said piston and cylinder each having a portion slidably engaging one another, said piston portion being externally exposed when said cylinder is raised, said cylinder extending downwardly from the table and terminating at a place below the anvil within said shell, whereby when the cylinder is raised the exposed portion of the piston is below the anvil and shielded by said shell, said outlet opening being in the neighborhood of the anvil and directing exhaust air outwardly therefrom between the anvil and the table.

5. A molding machine comprising a base, a shell projecting upwardly from said base and having at its upper end a striking anvil, said base being further provided with an inner tubular extension projecting upwardly therefrom and terminating below the striking anvil, a jolt table having on the underneath side thereof a surface for striking the anvil, a piston removably supported in said tubular extension and extending upwardly therefrom toward the jolt table, a cylinder surrounding the piston for raising the table relative to the anvil, said piston and cylinder defining an extensible fluid pressure chamber, an inlet for introducing fluid under pressure into said chamber to raise the jolt table relative to the anvil, an outlet through which fluid may be exhausted from said chamber for permitting the table to return by gravity and strike the anvil, said outlet being controllable by the relative movements of the piston and the cylinder, said piston and cylinder each having a portion slidably engaging one another, said piston portion being externally exposed when said cylinder is raised, said cylinder extending downwardly from the table and terminating at a place below the anvil within said shell, whereby when the cylinder is raised the exposed portion of the piston is below the anvil and shielded by said shell.
